RACK

Samuel Schoor, Newark, N. J., assignor, by mesne assignments, to Copper Clad Products Inc., Newark, N. J., a corporation of New Jersey.

Application May 19, 1949, Serial No. 94,150

9 Claims. (Cl. 211—105.1)

1

My invention relates generally to racks and specifically to racks having movable hooks thereon.

It is among the objects of my invention to provide a rack which will securely hold several utensils.

It is a further object of my invention to provide a rack with a number of movable hangers thereon which will permit spacing of the utensils suspended from the rack, in accordance with their special needs.

It is a further object of my invention to provide a rack which is easily attached to a wall or other surface.

Still a further object of my invention is to provide a rack which may be firmly attached to a wall and is resistant to the distorting influences of articles suspended therefrom.

Among the other objects of my invention is to provide a rack which is strong, easy to construct, relatively inexpensive and durable.

These objects and advantages, as well as many other objects and advantages, may be attained from the device illustrated in the drawings, in which:

Figure 1 is a view in perspective of a rack showing my invention;

Figure 2 is a view in perspective of a hanger as used on my rack;

Figure 3 is a view in perspective of the end bracket thereof;

Figure 4 is a side view of my rack; and

Figure 5 is a top plan view of my rack.

Referring now to the drawings in detail, my rack has a hanger bar or rod 11, preferably formed of metal. The bar has a bend 12 along its length so that it has two sides 13, 14. These sides 13, 14 are disposed to each other at an angle of approximately 120°. Thus the bend 12 forms a V-shaped rod thereby serving to strengthen the bar along its length and also serving to hold the hangers that ride on the bar against displacement.

The hangers 15 that ride on the bar have an upper hook 16 and a lower hook 17 formed thereon. The upper hook has a downwardly extending leg 18 and an upwardly extending leg 19. Likewise, the lower hook 17 has a downwardly extending leg 20 and an upwardly extending leg 21. These two hooks are connected by a V-shaped mid-portion or area 22 which has a bend 23 as near its center from which there extends a top leg 24 and a bottom leg 25. The upwardly extending leg 19 of the upper hook 16 joins the top leg 24 of the mid-portion 22 and the upwardly

2

extending leg 21 of the lower hook 17 joins the bottom leg 25 of the mid-portion 22.

The top leg 24 and the upwardly extending leg 19 are spaced away from each other sufficiently to allow the rod 11 to be intruded between them. The downwardly extending legs 18, 20 are disposed in parallelism to each other. Likewise, the upwardly extending legs 19, 21 are disposed in parallelism to each other, as will appear in Figure 4.

For attaching the rod 11 to a wall or other surface, end brackets 26 are provided. The end brackets 26 are triangular so that they may fit over the bar. The back 27 will space the rod 11 away from the wall so that the hangers 15 may freely slide on the rod 11 without touching the wall to which the rod is attached. The back 27 and the upper front 28 have attachment holes 29. The upper front 28 and the lower front 30 are disposed to each other at an angle of 120° to conform to the rod. The rod has holes 31 at each end corresponding to the holes 29 in the bracket so that an attaching nail may pass through.

When it is desired to attach my rack to the wall, the hangers 15 are slid onto the rod 11. The end brackets 26 are then slid onto the rod 11 until the holes 29 in the brackets 26 coincide with the holes 31 in the rod 11. A nail may then be used to attach the assemblage to the wall.

Once the rack is attached, the hangers 15 will freely slide on the rod 11, but cannot be removed. The mid-portions 22 of the hangers 15 conform to the shape of the rod 11 and distribute the weight of any object suspended from the hooks 16, 17 evenly on the rod. The spacing of the hangers 15 along the rod 11 is a matter of choice depending on the size of the objects suspended from the hooks 16, 17.

The angular disposition of the sides 13, 14 and the legs 24, 25 is subject to variation and is, of course, not critical. The materials of which the elements are formed may be metal or plastic, or any suitable material.

The foregoing device is intended merely to be illustrative of one embodiment of my invention. Many changes may be made in the construction, selection and arrangement of the various elements comprising my invention, all within the scope of the appended claims without departing from the spirit of the invention.

I claim:

1. A rack comprising a relatively thin V-shaped rod having substantially convex outer and concave inner sides, a hanger slidably positioned

on the rod, a V-shaped back portion of the hanger conforming to the inner side of the rod, and a front portion of the hanger connected to the back portion and conforming to a portion of the outer side of the rod, upwardly extending hooks connected to the front and back portions of the hanger, and a bracket extending across the back of the rod and in engagement with the front thereof.

2. A rack comprising a relatively thin V-shaped rod having substantially convex outer and concave inner sides, a hanger slidably positioned on the rod, a V-shaped back portion of the hanger conforming to the inner side of the rod, and a front portion of the hanger connected to the back portion and conforming to a portion of the outer side of the rod, upwardly extending hooks connected to the front and back portions of the hanger, a bracket extending across the back of the rod and in engagement with the front thereof, and the front upper portions of the bracket and rod having attachment holes in alignment, and the rear portion of the bracket having an attachment hole in cooperative alignment with the said holes.

3. A rack comprising a rod, substantially convex outer and concave inner sides on the rod, a hanger slidably positioned on the rod, a back portion of the hanger conforming to the inner side of the rod, and a front portion of the hanger connected to the back portion and conforming to a portion of the outer side of the rod, a bracket extending across the back of the rod and in engagement with the front thereof.

4. A rack comprising a rod, substantially convex outer and concave inner sides on the rod defined by a longitudinal bend thereon, a hanger slidably positioned on the rod, a back portion of the hanger conforming to the inner side of the rod, and a front portion of the hanger connected to the back portion and conforming to a portion of the outer side of the rod, and a bracket extending across the back of the rod and in engagement with the front thereof.

5. A rack comprising a relatively thin V-shaped rod having a substantially convex outer side and a substantially concave inner side, a hanger slidably positioned on the rod, a V-shaped back portion of the hanger conforming to the inner side of the rod and a front portion of the hanger connected to the back portion and conforming to the top portion of the outer side of the rod, upwardly extending hooks connected to the front and back portions of the hanger, an attachment bracket having a back portion extending across the back of the rod and intervening between the rod and the surface to which it is attached, and a front portion of the attachment bracket engaged with and conforming to the front of the rod.

6. A rack comprising a relatively thin V-shaped rod having a substantially convex outer side and

a substantially concave inner side, a hanger slidably positioned on the rod, a V-shaped back portion of the hanger conforming to the inner side of the rod and a front portion of the hanger connected to the back portion and conforming to the top portion of the outer side of the rod, upwardly extending hooks connected to the front and back portions of the hanger, an attachment bracket having a back portion extending across the back of the rod and intervening between the rod and the surface to which it is attached, and the front upper portion of the bracket and rod having attachment holes in alignment with each other, and the back portion of the bracket having an attachment hole in cooperative alignment with said holes.

7. A rack comprising a relatively thin V-shaped rod having substantially convex outer and concave inner sides, a hanger slidably positioned on the rod, a V-shaped back portion of the hanger conforming to the inner side of the rod, and a front portion of the hanger connected to the back portion and conforming to a portion of the outer side of the rod, upwardly extending hooks connected to the front and back portions of the hanger, and a bracket engaged with the rod.

8. A rack comprising a rod, substantially convex outer and concave inner sides on the rod, a hanger slidably positioned on the rod, a back portion of the hanger conforming to the inner side of the rod, and a front portion of the hanger connected to the back portion and conforming to a portion of the outer side of the rod, and a bracket engaged with the rod.

9. A rack comprising a rod, substantially convex outer and concave inner sides on the rod defined by a longitudinal bend thereon, a hanger slidably positioned on the rod, a back portion of the hanger conforming to the inner side of the rod, and a front portion of the hanger connected to the back portion and conforming to a portion of the outer side of the rod, and a bracket engaged with the rod.
